UNITED STATES PATENT OFFICE.

JOHN SCHIES, OF ANDERSON, INDIANA.

MECHANICAL MOVEMENT.

SPECIFICATION forming part of Letters Patent No. 657,456, dated September 4, 1900.

Application filed January 18, 1900. Serial No. 1,892. (No model.)

To all whom it may concern:

Be it known that I, JOHN SCHIES, residing at Anderson, in the county of Madison and State of Indiana, have made certain new and 5 useful Improvements in Mechanical Movements, of which the following is a specification.

My invention is an improvement in mechanical movements seeking to provide a 10 novel construction whereby a plunger within a revolving carrier or body may be caused to move longitudinally within said body or carrier as the latter is revolved; and the invention consists in certain novel constructions 15 and combinations of parts, as will be herein-after described and claimed.

In the drawings, Figure 1 is a side elevation of an apparatus embodying my invention. Fig. 2 is an end elevation, one half of 20 the box or carrier being removed. Fig. 3 is a sectional view on line 3 3 of Fig. 2. Fig. 4 is a view similar to Fig. 2, showing the carrier in a different position and the plunger set to a different position because of the change 25 of position of the carrier; and Fig. 5 is a detail view of the plunger and its operating parts detached.

My invention is designed for use in connection with a bottle and jar blowing machine, but it can be adapted to and used in other machines wherever it may prove useful.

In the construction shown I employ a suitable framing composed of the uprights A A, to which are fixed the outer ends of the bearing-pieces B B, which are held from turning 35 in said frame by any suitable means. I have shown for this purpose pins B², which key the bearings to the frames A, and I have also shown the said bearings as extended beyond the 40 frames A and having their ends threaded to receive the nuts B³. At their inner ends the bearing-pieces are provided with crank-like arms C C', and the bearing-pieces are alike, except that the wrist-pin D projects from the 45 arm C' and enters a socket D' in the arm C.

The bearing-pieces B B' are provided with the spindles E, on which are journaled the sections of the body or carrier presently described. This body or carrier F is provided 50 with openings which journal upon the spindles E, so the said body or carrier can be revolved freely upon said spindles. Guide-

openings are formed in the body or carrier at diametrically-opposite points and receive and guide the plunger G, so the latter can be 55 moved longitudinally within the carrier.

In connection with the carrier and the plunger movable longitudinally therein I provide means for moving the plunger longitudinally as the carrier is revolved. I prefer to arrange this means for moving the plunger within the carrier and also to employ the construction shown in connection with the special construction of plunger which I will now describe.

The plunger G is preferably formed of a length greater than that of the carrier, so it can be protruded beyond the end of the carrier, and I form the plunger, at a point midway between its ends, with a yoke G', having 60 a slot G², elongated at right angles to the direction of length of the plunger and adapted to receive the pin D before described, which extends within the slot G² and is preferably supplied with a roller D² to reduce the friction.

It will be noticed from Figs. 2, 3, and 70 4 that the pin D is eccentric to the spindles E and in the construction shown has its axis arranged above that of such spindle. As the carrier revolves on the spindles and such spindles are held from turning and the yoke of the plunger is engaged by the crank-pin D, which is in fixed relation with the spindles, it is evident that as the carrier is 75 revolved it will give a longitudinal movement 80 to the plunger. Thus, referring to Fig. 2, if the carrier be given a half-turn it will cause the plunger to move in such carrier in such manner as to cause the lower end of the plunger in Fig. 2, which is now retracted, to 85 come to the top and be protruded beyond the carrier, as shown. This is also indicated in Fig. 4, in which the carrier has been partially revolved and the plunger has been moved to cause both its ends to protrude slightly, as 90 shown in said Fig. 4. The crank-arms C and C' operate as guides for both the carrier and the plunger, as will be understood from Fig. 3.

For convenience in manufacturing and assembling the parts it may be preferred to 100 form the carrier in two sections, as indicated in Figs. 1 and 2, such sections being secured when applied for use by dowel-pins and screws, as shown in the drawings.

It will be noticed that as the body or carrier is turned or revolved the plunger is operated longitudinally, so that it always protrudes at the top of the carrier and disappears at the bottom. As will be understood by those skilled in the art of glass-making, the purpose is to use the plunger on the top and partly make a bottle or jar in connection with the necessary mold, and when this first operation has been completed the carrier is to be turned half-way over, when the plunger will be out of the way, so air can be applied to allow the next operation to be effected by blowing and the bottle or jar be completed.

Having thus described my invention, what I claim, and desire to secure by Letters Patent, is—

1. The combination substantially as described of a revolving body or carrier, a plunger moving with and also movable longitudinally in the carrier as the latter is revolved and arranged to protrude alternately at its opposite ends beyond the carrier, and means for moving the plunger longitudinally during the revolution of the carrier.

2. The combination of a revolving body or carrier, a plunger movable longitudinally in the carrier and arranged to protrude alternately at its opposite ends beyond the carrier and means within the carrier by which to move the plunger longitudinally as the carrier is revolved.

3. The combination of the framing, the bearings for the carrier, the crank-pin eccentric to said bearings, the carrier supported and arranged to be revolved on said bearings, and the plunger movable longitudinally within the carrier and having between its ends a yoke for engagement by the crank-pin and arranged to protrude alternately at its opposite ends beyond the carrier substantially as set forth.

4. The combination of the bearing-pieces

having spindles forming bearings for the carrier, crank-arms forming guides, and the crank-pin between said crank-arms and eccentric with respect to the spindles, the carrier arranged to revolve on the spindles, and the plunger movable longitudinally in said carrier and provided between its ends with means for engagement by the crank-pin and arranged to protrude alternately at its opposite ends beyond the carrier substantially as set forth.

5. An apparatus substantially as described comprising the carrier-body composed of a box formed in sections having in their abutting faces bearings for the plunger, a support on which said carrier is journaled to revolve, a plunger movable longitudinally in the carrier, and means within the carrier for operating the plunger longitudinally as the carrier is revolved, substantially as set forth.

6. The combination of the opposite bearing-pieces having spindles, the crank-pin extending between said pieces and arranged eccentric to the spindles thereof, the carrier revolving on the spindles, and the plunger movable longitudinally in the carrier and engaged between its ends with the crank-pin and arranged to protrude alternately at its ends beyond the carrier substantially as set forth.

7. The combination of the framing-uprights, the bearing-pieces held thereto and having spindle portions and a crank-pin extended between said bearing-pieces and arranged eccentric to the spindle portion, the carrier composed of the box-sections journaled on the spindles and having in their abutting faces bearings for the plunger, and the plunger having between its ends a yoke for engagement by the crank-pin substantially as set forth.

JOHN SCHIES.
